UNITED STATES PATENT OFFICE.

WYNN MEREDITH, OF ALAMEDA, CALIFORNIA, ASSIGNOR TO PETROLEUM RECTIFYING COMPANY, OF SAN FRANCISCO, CALIFORNIA, A CORPORATION OF CALIFORNIA.

STRATIFYING DEHYDRATOR.

Application filed April 30, 1921. Serial No. 465,909.

To all whom it may concern:

Be it known that I, WYNN MEREDITH, a citizen of the United States, residing at Alameda, in the county of Alameda and State of California, have invented a new and useful Stratifying Dehydrator, of which the following is a specification.

My invention relates to dehydrators which are used for separating emulsified water from oil and it is particularly applicable to dehydrators used to separate water from petroleum emulsions.

The principal object of the invention is to provide a dehydrator which will be adapted to treat oils of widely different characteristics.

A further object of the invention is to provide a dehydrator having a layer of high dielectric strength in the electric field.

A still further object of the invention is to provide a dehydrator in which the porcelain insulation is so disposed that it is kept clean by a current of dehydrated oil.

Further objects and advantages will be made evident hereinafter.

Referring to the drawings which are for illustrative purposes only,

Fig. 1 is a side elevation partly in section showing one form of my invention.

Fig. 2 is a plan view of same.

Fig. 3 is a diagram illustrating the character of the electric field.

Referring to these drawings, the apparatus illustrated consists of a dehydrator tank 11, a centrifugal pump 12 and a settling tank 13. The tank 11 forms the dehydrator proper and is of cylindrical form having a tight bottom 14 and a tight top 15. Passing through the top is a porcelain insulator 20 which has a central opening through which a conductor 21 passes, this conductor being attached to a rod 22 which supports the inner electrode 30. The tank 11 forms the outer grounded electrode. The

inner electrode 30 consists of a cylindrical shell 31 joined to an inverted funnel 32 at the bottom and to a draft tube 33 at the top. One or more intermediate discs 34 may be secured to the cylinder 31. A transformer 35 having a low tension primary 36 and a high tension secondary 37 is provided. One side of the secondary 37 is connected through a wire 38 with the tank 11 and the other side being connected through a wire 39 with the conductor 21. A reversing plate 40 is

provided in the top of the treater having the general form shown and a perforated induction pipe 41 is placed inside the top of the tank 11 and outside the member 40 being fed by an emulsion inlet pipe 42 provided with a valve 43. The lower portion of the tank 11 is connected through an outlet pipe 50 with a perforated pipe 51 which is situated in the bottom of the settling tank 13. A swing pipe 52 is placed in the settling tank 13 being adapted to be swung up and down by means of a cable 53 and a winch 54. The pipe 52 is connected through a valve 55 with the suction side of the centrifugal pump 12 which may be conveniently driven by an electric motor 56. A by-pass pipe 57 controlled by a valve 58 connects the pipe 50 with the suction of the pump 12. The pressure side of the pump is connected to a pipe 59 having a flow valve 60, this pipe 59 being connected to a nozzle 61 placed similarly inside the tank 11 and directed upwardly therein.

The method of operation is as follows:

The tanks 11 and 13 are first filled with oil, any gas or air in the top of the tank 11 being relieved through a gas vent 70. As soon as the apparatus is filled with the oil to be treated the primary 36 is energized thus generating an alternating electro-motive force of about 11,000 volts in the secondary 37, this electro-motive force being impressed between the tank 11 and its connected parts, and the inner electrode 30. Intense electrostatic fields are set up between the edges of the members 32, 33 and 34 and the inner surface of the tank 11. These electrostatic fields tend to establish arcs or conducting chains through the water particles thus tending to short-circuit the secondary 37. This short-circuiting tendency can be overcome by agitation which can be readily produced by the pump 12.

In starting the dehydrator, I prefer to close the valve 55 and to open the valve 58 thus circulating fluid from the bottom of the tank 11 upwardly through the cylinder 31 and downwardly through the electric fields at the edges of the members 32, 33 and 34. The rate of flow can be readily controlled by the valve 60 which is manipulated to control the rate of flow so that excessive disruptive discharges do not take place in the electric fields. The contents of the treater 11 are soon partially dehydrated

to a sufficient degree. The valve 58 may then be closed and the valve 55 opened, the swing pipe 52 being adjusted about as shown in the drawing. Oil is now taken from the 5 top of the settling tank 13 passing upwardly through the cylinder 31 and downwardly through the electric field, this oil being partially dehydrated in its passage there-through i. e. the particles of water in the 10 emulsion are agglomerated into larger masses which are passed through the pipe 50 and the perforated pipe 51 into the settling tank. In the settling tank, the water tends to settle out into the bottom 15 of the tank from which it may be removed either automatically or by means of a pipe 80 controlled by a valve 81. This circulation of oil from the top of the trap tank through the treater is continued until the 20 oil in the top of the trap tank is relatively free from water particles at which time the di-electric strength of this oil becomes so great that practically no current is taken by the treater and the dehydration ceases 25 for lack of water to operate on. When this condition is obtained, the valve 43 is opened and a flow of wet oil is started into the interior of the tank 11. This wet oil flows downwardly along the inner wall of the 30 tank outside the edge of the deflector 50 forming a wet outer envelope or cylinder of wet oil which entirely covers the inner wall of the treater 11. This outer envelope or cylinder of wet oil is outside and immediately adjacent to a similar moving cylinder of dry oil which is circulated by the pump 12. The result is that each of the 35 electric fields consists of a layer of dehydrated oil inside of a layer of extremely wet emulsion. The dry oil prevents disruptive discharges between the members 32, 33 and 34 in the tank 11 at the same time 40 promoting the dehydration.

It will be noted that the insulator 20 projects downwardly to the center of the rapidly moving stream of dry oil which is of high enough velocity to prevent deposits from forming on the insulator thus preventing breakage of insulators. It is sometimes necessary to circulate oil from the 45 bottom of the settling tank 13 through the tank 11 and this may be accomplished by lowering the swing pipe by means of the winch 54 so that oil is taken from near 50 the bottom of the treater. The condition

in the electric field is diagrammatically illustrated in Fig. 3 in which the small drops 90 represent water particles. It will be seen that these water particles are extremely concentrated on the outside of the 60 flowing stream being relatively few near the center.

I claim as my invention:

1. In a dehydrator for emulsions, the combination of: a charged electrode supported in and surrounded by the emulsion to be treated; and means for surrounding said electrode with a fluid envelope of higher di-electric strength than the emulsion to be treated. 65
2. In a dehydrator for emulsions, the combination of: a charged electrode supported in and surrounded by the emulsion to be treated; and means for surrounding said electrode with a moving fluid envelope 70 of higher di-electric strength than the emulsion to be treated. 75
3. A method of preventing disruptive discharges between electrodes immersed in an emulsion which comprises: maintaining 80 in the space between said electrodes a continuous layer of fluid material having a higher di-electric strength than said emulsion.
4. In a dehydrator, the combination of: 85 a vessel containing the emulsion to be treated; means for establishing an electric field in the emulsion in said vessel; and means for maintaining in said field a layer 90 of fluid material having a higher di-electric strength than the oil to be treated.
5. In a dehydrator, the combination of: a vessel containing the emulsion to be treated; means for establishing an electric field in the emulsion in said vessel; and means for 95 maintaining in said field a moving layer of fluid material having a different di-electric strength than the oil to be treated.
6. In a dehydrator, the combination of: 100 a vessel containing the emulsion to be treated; means for establishing an electric field in the emulsion in said vessel; and means for maintaining in said field a moving layer of fluid material having a higher di-electric strength than the oil to be treated. 105

In testimony whereof, I have hereunto set my hand at San Francisco, California, this 18 day of April 1921.

WYNN MEREDITH,
